CLAIM

The ornamental design for blender attachment, as shown and described.

DESCRIPTION

FIG. 1 is a perspective view of the blender attachment, showing our new design first embodiment;

FIG. 2 is a front view of the embodiment shown in FIG. 1; FIG. 3 is a side view of the embodiment shown in FIG. 1; FIG. 4 is rear view of the embodiment shown in FIG. 1; FIG. 5 is another side view of the embodiment shown in FIG. 1;

FIG. 6 is a top view of the embodiment shown in FIG. 1; and,

FIG. 7 is a bottom view of the embodiment shown in FIG. 1.

The broken lines in the figures are for environmental purposes only and form no part of the claimed design.

The dash dot line form no part of the claimed design, but is instead intended to delimit claimed subject matter from unclaimed subject matter.

1 Claim, 7 Drawing Sheets(56)
